METHOD FOR PURIFYING LACTOFLAVIN

George E. Flanigan and George C. Supplee,
Bainbridge, N. Y.No Drawing. Application March 2, 1938,
Serial No. 193,518

11 Claims. (Cl. 167—31)

This invention is concerned with a method for purifying lactoflavin and involves an improvement over the procedure described in copending application Serial No. 61,890, filed February 1, 1936, which application resulted in Patent No. 2,186,314, January 9, 1940.

We have found that lactoflavin, as contained in natural products is more readily soluble (colloidal as distinguished from crystalloidal) than when freed from extraneous matters commonly associated with it. Although it is not intended to limit the invention to any particular theory of operation, we believe that the lactoflavin as contained in natural products is physically or possibly loosely chemically combined with certain basic types of natural products which serve to hold it in solution at higher concentrations than when it exists in free form.

It is an object of the present invention to provide an improved procedure whereby pure lactoflavin may be separated in crystalline form. It is also an object to provide an improved procedure by which extraneous matter, associated with the lactoflavin in natural products, may be separated from the lactoflavin to an extent making it possible to crystallize the pure lactoflavin from a solution in which the natural product would be soluble. A further object of the invention is to provide a process for obtaining pure crystalline lactoflavin without resorting to the formation of intermediate salts of the product and subsequent decomposition thereof as an integrated step in the process of isolation of this material. It is another object to provide a method which involves crystallizing lactoflavin from the same active solvent used for its initial elution and solution from an inert material with which it is associated. It is also an object to disclose a method of producing pure lactoflavin involving the use of not more than four common solvents or precipitants, namely water, acetone, alcohol and ethyl ether, certain of which substances may at one time act as precipitants for lactoflavin and at another time as solvents or selective eluting agents. Other objects will become apparent.

The present invention is particularly concerned with the purification of lactoflavin and its separation from extraneous matter associated with it in solution in water or in an acetone-water mixture. The original source of the lactoflavin may be from milk or from other materials containing this compound. In using the term lactoflavin it is intended to include flavins from sources other than milk and sometimes referred

to as riboflavin. A convenient source is from a crude lactoflavin concentrate, which concentrate may be obtained from milk in accordance with United States Patent No. 2,006,699, issued July 2, 1935, or by some other process. It may also be obtained from whey and other solutions containing lactoflavin.

In the separation of lactoflavin from products containing it in solution, the lactoflavin may be adsorbed on a suitable adsorbate, such as fuller's earth, and may be separated from that adsorbate by elution with an acetone-water solution as described in the above mentioned copending application. The adsorption is accomplished in an acid solution, for example, at a pH ranging from about 1 to just under 7, a preferred range being about 4.5 to 5.5. This acidity may be obtained by adding hydrochloric or some other suitable acid. The elution may be accomplished with an acetone-water mixture containing, for example, 60 to 85% acetone and preferably containing acetone in the proportion of about 75 to 80 or 82% of the mixture. When lower concentrations of acetone are used in the acetone-water mixture, such mixtures elute a relatively higher proportion of the inert or extraneous material with the lactoflavin. Likewise when higher percentage concentrations of acetone are employed (in all cases in the presence of some water), such higher concentrations of acetone are relatively less effective in eluting the lactoflavin.

The proportions of the acetone-water mixture to dry material may vary within wide limits dependent upon the equipment used, time relationships and other factors. Proportions as high as 300 or 400 parts by weight of the mixture and as low as seven parts by weight or less of the mixture to one of dry material have been found satisfactory. The temperature of the elution is not important except that somewhat greater efficiency is obtained at higher temperatures. With suitable equipment to prevent loss of acetone and volatilization, temperatures above the boiling point of the acetone mixture may be used. These preliminary steps in the preparation of the eluate are merely illustrative, it being obvious that the invention will be useful with solutions of the lactoflavin prepared under other conditions.

As a specific example of the preparation of a solution of lactoflavin, 6000 lbs. of fluid lactoflavin or vitamin concentrate, prepared as described in the patent referred to above and containing from 20 to 28% total solids, is placed in an appropriate vat or tank with a suitable high

speed agitator. To this quantity of fluid concentrate there is added 50 lbs. of commercial muriatic acid (sp. gr. about 1.8). The mixture is agitated to secure uniformity and 150 lbs. of a suitable adsorbant grade of fuller's earth is then added. The total mixture is subjected to rapid agitation for a period of about 20 minutes, although the time of agitation is not critical. Also, the temperature of the material is not critical since adsorption may be efficiently carried out at ordinary temperatures or at temperatures even approaching the boiling point of the mixture. Following the agitation period an amount of water is added sufficient to bring the total weight, exclusive of the fuller's earth up to about 8000 to 8250 lbs. The addition of the extra water at this stage is not vital to the process but its addition is made to reduce the relative viscosity of the mixture and to facilitate settling of the suspended fuller's earth.

Following the addition of the extra amount of water the mixture is allowed to stand, without further agitation, until the fuller's earth has settled to a degree to permit decantation of practically all of the fluid. The fluid is decanted and the fuller's earth is washed with water a number of times by agitation, settling and decanting, and after the last washing and decanting the fraction containing the solids may be filtered in an ordinary filter press in accordance with usual procedure. The filter cake containing the suspended fuller's earth on which is adsorbed the lactoflavin and other impurities may be dried in a tunnel dryer or by any other appropriate means, preferably slowly and with exposure to air, or the wet filter cake may be used directly. In the latter case the moisture or water content of the press cake should be ascertained and account taken of the amount of water present in order to regulate the percentage of acetone in the acetone-water mixture to be used in the following steps.

In the next step of the process, 72 lbs. of the dry fuller's earth adsorbate (or an equivalent amount of filter press cake based upon the dry solids content) prepared as described above is placed in an appropriate tank equipped with a high speed agitator. To this quantity of dry material there is added 500 lbs. (about 7 to 1 by weight) of a neutral mixture of water and acetone containing about 80% acetone in the aqueous mixture.

The fuller's earth adsorbate and the acetone-aqueous mixture are subjected to violent agitation while heating the mixture to about 50 to 55° C. The agitation is continued for a period of not less than 15 to 20 minutes, although periods of from 1 to 2 hours may be employed. Following the agitation period the fuller's earth is allowed to settle, which settling or precipitation at this stage is very rapid, leaving a clear yellow or greenish-yellow supernatant liquid. This supernatant liquid containing the lactoflavin is decanted off and the residual fuller's earth is subjected to the same elution method for a successive number of times. It has been ascertained that with the material under consideration from 50 to 60% of the lactoflavin is eluted on the first treatment. Additional elutions release a progressively lesser amount of lactoflavin. It has been determined however that in practically all cases four successive elutions carried out as described will release from 80 to 95% of the lactoflavin. If it is desired the elution may be continued until all lactoflavin is released. Economy and practical contingencies dictate the degree of recovery

of the lactoflavin from the fuller's earth at this stage. The number of elutions may be materially decreased by using larger volumes of the acetone-water mixture per unit amount of the dry fuller's earth adsorbate.

The above procedure is merely illustrative of a method suitable for producing a solution of lactoflavin with which our invention may be used and it is not intended to limit the invention to the particular procedure or details described for preparing the solution. For instance, the invention may be applied to other extracts of the dried adsorbate containing lactoflavin or to other aqueous or acetone-aqueous solutions of the lactoflavin.

In applying our improved procedure to the separation of lactoflavin from a solution of it prepared as described above, the supernatant liquors from the successive elutions are combined and the acetone distilled off. Not only is all acetone removed but the residual water is partially removed at this stage. If, for example, four elutions are made each with 500 lbs. of 80% acetone-water mixture there would remain substantially 400 lbs. of water after removal of the acetone. This amount of water is evaporated in a vacuum pan, to a total quantity of about 6 to 12 pounds. The extent to which the solution is to be concentrated will depend upon various factors including the concentration of lactoflavin and the concentration and nature of the extraneous matter. For instance, in some cases concentrations to 2 to 4 pounds have been found to be satisfactory while in others the concentration is stopped at 15 or more pounds. Concentrations in which the lactoflavin is present in the proportions of 2 to 3½ milligrams per cubic centimeter of solution have been found suitable. This concentration should be to such a degree as to partially precipitate the extraneous impurities but to retain the lactoflavin in solution.

The residual 6 to 12 lbs. (or other quantity) of water containing the lactoflavin from the original 72 lbs. of fuller's earth adsorbate, together with any precipitate formed therein, is treated with 95% ethyl alcohol, using sufficient amount of alcohol so that the final mixture of water and alcohol has a 50% alcohol concentration by weight. This treatment with alcohol results in the formation of a precipitate which forms on standing and usually has completely precipitated after a period of 8 to 12 hours. The concentration of alcohol used in this treatment is such as is effective in precipitating colloidal fuller's earth. Other materials that will accomplish this separation of the fuller's earth without deleterious effect upon the lactoflavin may be used.

The precipitate resulting from the alcohol treatment is filtered off and the filtrate taken to the next step of our process (the handling of this precipitate for the recovery of the adsorbed or occluded lactoflavin which it contains will be described later). The alcohol contained in the filtrate is boiled off and the remaining aqueous portion further concentrated under vacuum to a final volume of about 800 to 1000 cc. This aqueous volume now contains the greater portion of the lactoflavin contained on the original 72 lbs. of fuller's earth adsorbate.

To this 800-1000 cc. of aqueous solution of impure lactoflavin there is added pure neutral acetone to give a ratio of about 10 volumes of acetone to 1 volume of the aqueous portion. The mixture is thoroughly agitated and allowed to

stand from $\frac{1}{2}$ to 1 hour. A gummy residue rapidly forms and settles out. The clear supernatant liquor is decanted off. The gummy residue is redissolved in a small volume of water (about 1500 cc.). To this redissolved gum, about 1500 cc. volume, pure acetone is added to give a final ratio of 10 volumes of acetone to 1 of water. The gummy residue rapidly settles out and the supernatant liquid may be decanted or filtered.

The optimum concentrations and quantities of acetone-water mixture in this step depend upon the quantity and character of the extraneous material to be precipitated. Ratio of 1:5 or 1:15, (water:acetone) for example, may be employed. Increased concentration of acetone will favor increased precipitation of extraneous matter and will also favor crystallization of lactoflavin at this point. Thus if the concentration of acetone is too high the lactoflavin itself may crystallize out. It is desirable to avoid this at this step but if it should occur the crystals may be filtered out and added to the solution from which the final crystallization of lactoflavin is accomplished. If the concentration of acetone is too low, the material which it is desired to precipitate would not be completely precipitated and flocculated into a coalescent gummy material.

The combined decanted liquors now holding the lactoflavin in solution in an acetone-aqueous mixture is freed from acetone by boiling and the aqueous portion further concentrated to about 600 cc.

This 600 cc. aqueous portion is extracted four consecutive times with new 800 cc. portions of ethyl ether. This extraction is readily accomplished in the ordinary separatory funnels and the ether fraction, containing extraneous matter removed from the lactoflavin is separated from the aqueous fraction containing the lactoflavin.

Following the ether treatment of the aqueous portion, ether is removed by decantation and boiling, and pure neutral acetone is again added to the 600 cc. aqueous portion to give a ratio of about 10 volumes of acetone to 1 of water in the aqueous solution. A gummy residue is again formed on standing for a short period. The supernatant liquor is filtered off and the gummy residue dissolved in a minimum amount of water (about 500 cc.), and this aqueous solution again subjected to treatment with 10:1 acetone. The gummy residue is removed by filtration and the supernatant liquids combined.

At this stage the lactoflavin in the original fuller's earth adsorbate is now contained in a 10:1 acetone-water mixture. This mixture is now boiled to remove part of the acetone. The boiling or removal of the acetone at this stage should proceed with care, the amount of acetone removed being only that amount necessary to bring the acetone content of the mixture down to 70% of acetone by weight, with a specific gravity of the mixture in the neighborhood of 0.875. This 70% acetone-water mixture containing the lactoflavin treated as already described is now placed in any suitable receptacle protected from the light and at about ordinary room temperatures. Crystallization of pure lactoflavin will ordinarily start within a period of 12 to 18 hours and completion of the crop of crystals will ordinarily have been reached within a period not exceeding 5 days. The crystallization of the pure lactoflavin can be readily recognized by the formation on the sides and at the bottom of the container

of brilliant yellow or orange-yellow burr-like masses of the pure material. These crystallization nuclei develop in size and number up to a period of about 5 days. It is desirable to avoid fast crystallization, a suitable rate being such that it starts after standing about 18 hours at room temperature and is completed in four to five days. If the solution is allowed to stand for a longer time extraneous matter dissolved in the solution may separate out.

It is to be noted that in this step the acetone serves a function directly the reverse of the function of the acetone and water concentration previously used in the procedures described above. In this stage of the process the acetone-water concentration must be such that the acetone constituent acts as an agent initiating and facilitating the crystallization of the lactoflavin while in the preceding step its function is to retain the lactoflavin and precipitate extraneous matter. Also at this stage the water must be present in such relative proportions that certain extraneous material will be held in solution thus permitting the crystallization of the pure lactoflavin facilitated by the appropriate amount of acetone. Thus the lactoflavin, from which extraneous matter associated therewith has been separated by the preceding procedures, may be crystallized from a solution in which lactoflavin, having extraneous material associated with it, would be retained in solution. Certain acetone and water relationships have been given in the specific example but it is apparent that these relationships might vary somewhat, such variance being dependent upon the exact or relative amount of lactoflavin in proportion to the extraneous matter present.

Following completion of the crystallization period the supernatant liquor is decanted and the crystal crop confined to a small volume in the mother liquor. It has been found most expedient to centrifuge this crystal mass rather than subject it to filtration. After removal of the mother liquor by decantation and centrifuging the crystals are washed with pure acetone in appropriate volume and by usual procedures but involving decantation and centrifuging in preference to filtration. The acetone washing is repeated two or three times. Following the washing of the crystals with acetone they are further washed 2 or 3 times with cold 95% alcohol employing the decantation and centrifuging manipulation. Following the washing with alcohol the crystals are further subjected to washing a number of times with ethyl ether employing the decantation and centrifuge method.

Following the final ether wash the crystals may be dried, preferably in air with or without added heat.

The yield of crystals obtained by the process described will of course depend upon the amount of lactoflavin originally contained in the crude lactoflavin concentrate employed; also the yield of crystals will be dependent upon the number of elutions of the dry adsorbate which practical circumstances may dictate.

The yellow or orange-yellow satin or thread-like crystals of lactoflavin obtained by the process described are readily recognized by microscopic examination, melting point, solubility, biological activities and other characteristics.

If for reasons determined by the operator it should be desired to subject the crystals obtained in a further resolution and crystallization the following procedures may be used.

The washed, dried and solvent-free crystals are re-dissolved in water by continued boiling. The aqueous solution of lactoflavin is slowly cooled but without unusual precaution and upon cooling and standing the lactoflavin readily crystallizes in masses of thread-like or needle-like crystals within a period of 12 to 18 hours, depending upon the initial concentration and the rate of cooling. If desired these crystals as obtained from the aqueous solution may be washed with acetone, 10 alcohol, and ether or they may be recovered without washing with all or any of the solvents mentioned, depending upon desires of the operator.

The precipitate obtained as the result of treating the concentrated aqueous solution of crude lactoflavin with 50% alcohol by weight as previously described contains substantial amounts of lactoflavin adsorbed on the flocculated fuller's earth and other flocculated impurities precipitated by the 50% alcohol. In many cases it will be found expedient to recover the lactoflavin adsorbed or occluded in this precipitate. Recovery of the lactoflavin from this material may be accomplished for example by returning it to a new 25 lot of fuller's earth and reprocessing it with the fuller's earth in the same identical manner as already described. Or the precipitate may be treated independently of a new lot of fuller's earth, using the sequence of steps and procedures which have been presented in detail as applicable to fuller's earth but with appropriate adjustment of the volume of acetone and water mixtures to conform with the smaller volume of inert material and the relatively larger volume or amount of lactoflavin which this precipitate carries in proportion to the inert material.

In a further modification of the process the initial elution of the fuller's earth adsorbate with 30% acetone and the next following steps may be carried out as previously described up to the point where the aqueous solution of concentrated lactoflavin is reduced to about 6 to 12 pounds. Instead of treating this concentrated aqueous solution with 50% alcohol the following sequence of procedures may be used. The mass may be further condensed in vacuo to a thick consistency, removed from the influence of vacuum and completely dried in the air or in usual types of drying tunnels. Slow drying of the material in the presence of air is desirable. The dried material is leached or simply boiled or extracted with water which dissolves the lactoflavin irrespective of the form in which it may exist at this stage. Redissolving of the dried material however with water does not put into solution all extraneous matter previously existing in solution prior to the drying of the material. A large proportion of inert matter remains insoluble in water, a substantial proportion of this inert material is 45 also insoluble in acetone, alcohol or ether following the drying operation which has been mentioned. The water extract from which the water insoluble material has been filtered (effective and rapid filtration of the insoluble matter may be 50 accomplished) is condensed to a small volume (about 500 to 600 cc.) and this concentrate is then subjected to the same sequence of steps as previously described beginning at the point where the 10 to 1 volume of acetone was first mentioned 55 in the preceding process.

This alternative method is illustrative of a modification of our procedures wherein we employ the effective agency of bringing the concentrate following initial elution with 80% acetone 60

to complete dryness as a means for effectively removing at the stage mentioned a large proportion of inert matter free or substantially free from lactoflavin by virtue of the fact that the drying operation, particularly in the presence of oxygen, renders certain components of the concentrate insoluble in water thus enabling a simple water extraction or solution of the lactoflavin as a method of removal at the particular stage and prior to proceeding with further details of the method necessary for the final preparation of pure crystalline form of lactoflavin. The alternative method also eliminates from the process as a whole the separate treating of the precipitate formed by treatment with 50% alcohol and it likewise eliminates retreating the alcohol precipitate as suggested in the previous discussion.

Instead of following the procedures described above for treatment of the acetone-water (10:1) precipitation or the alcohol precipitation, these precipitates may be reduced to complete dryness as described in the modified procedure described above and the lactoflavin may be leached from the dried precipitate with water, the water extract being returned at an appropriate place in the operation. In such operations the drying is preferably slow and in the presence of air, whereby concurrent physical and chemical changes (possibly oxidation, polymerization, condensation and/or dehydration) render the inert extraneous material insoluble in alcohol, acetone, ether and water. These changes are apparently accentuated by heat.

It is obvious that many variations in and other applications of the process described above may be made in utilizing our invention and it is not intended to limit the invention to the particular embodiments described. Various temperatures, times, concentrations, etc. may be more suitable in other particular applications of the invention, as will be recognized by ones skilled in the art. Also, the particular sequence of steps described need not be followed and certain of the steps may be omitted where the results of such steps are not required in the particular treatment or for the particular purpose involved. The terms used in describing the invention have been used in their descriptive sense and not as terms of limitation and it is intended that all equivalents thereof be included within the scope of the appended claims.

We claim:

1. In the preparation of crystalline lactoflavin, the steps of concentrating an acetone-water solution of lactoflavin and extraneous matter, separating extraneous matter therefrom by alcohol precipitation and ether extraction, treating an aqueous solution of the lactoflavin with acetone to precipitate extraneous matter, removing the acetone precipitated materials and concentrating the acetone-water mixture containing lactoflavin to lower the proportion of acetone therein to a degree which permits crystallization of the lactoflavin while maintaining extraneous materials in solution.

2. In the preparation of crystalline lactoflavin, the steps of concentrating an acetone-water solution of lactoflavin and extraneous matter derived from an adsorbate, separating extraneous matter therefrom by alcohol precipitation and ether extraction, treating an aqueous solution of such lactoflavin concentrate with acetone to precipitate extraneous matter, removing the acetone precipitated materials and drying them in air,

leaching the dried material with water and combining such water solution with the acetone-water fraction from the acetone precipitation, and concentrating the acetone-water mixture containing lactoflavin to lower the proportion of acetone therein to a degree which permits crystallization of the lactoflavin while maintaining extraneous materials in solution.

3. In the preparation of crystalline lactoflavin, the steps of concentrating an acetone-water solution of lactoflavin and extraneous matter from which extraneous matter capable of being precipitated by alcohol has been removed, treating such aqueous solution of the concentrated lactoflavin with acetone to precipitate extraneous matter, removing the acetone precipitated materials, concentrating the fluid fraction to remove acetone, extracting with ethyl ether and separating the ether fraction, removing the ether from the aqueous fraction and treating with acetone to precipitate extraneous matter, removing the acetone precipitate matter, and concentrating the acetone-water mixture containing lactoflavin to a degree which permits crystallization of the lactoflavin while maintaining the remaining extraneous materials in solution.

4. In the preparation of crystalline lactoflavin, the steps of concentrating an acetone-water solution of lactoflavin and extraneous materials, treating such concentrate with ethyl alcohol to precipitate extraneous materials, removing the alcohol precipitate and alcohol, separating the ether extractable matter therefrom, treating the resulting aqueous solution with acetone to precipitate extraneous materials while keeping the lactoflavin in solution, removing the acetone precipitated materials and concentrating the acetone-water mixture containing lactoflavin to a degree which permits crystallization of the lactoflavin while maintaining extraneous materials in solution.

5. In the preparation of crystalline lactoflavin, the steps of concentrating an acetone-water solution of lactoflavin derived from milk and extraneous materials, treating such concentrate with ethyl alcohol to precipitate extraneous materials, removing the alcohol precipitate and alcohol, drying the precipitate in air and leaching it with water, separating the leach solution and combining it with the liquid portion from the alcohol precipitation, extracting the solution with ether, treating the mixture with acetone to precipitate extraneous materials while keeping the lactoflavin in solution, removing the acetone precipitated materials and concentrating the acetone-water mixture containing lactoflavin to a degree which permits crystallization of the lactoflavin while maintaining extraneous materials in solution.

6. In the preparation of crystalline lactoflavin, the steps of concentrating an acetone-water solution of lactoflavin and extraneous material derived from an adsorbate, drying the concentrate in air, leaching the dried concentrate with water, extracting the aqueous solution with ether, treating the resulting solution with acetone to precipitate extraneous matter, removing the acetone precipitated materials and concentrating the acetone-water mixture containing lactoflavin to a degree which permits crystallization of the lactoflavin while maintaining extraneous materials in solution.

7. In the preparation of crystalline lactoflavin the steps of eluting an adsorbate containing lactoflavin with a mixture of acetone and water

5 containing about 30% acetone, concentrating the eluate and drying the concentrate in air, leaching the dried material with water, adding acetone to the separated leach solution to give a concentration of about 10 parts by volume of acetone and 1 part of water, separating the extraneous matter precipitated thereby, heating to remove the acetone, extracting the liquid with ethyl ether, removing the ether and adding acetone to give a concentration of 10 parts of acetone and 1 of water, separating any residue, concentrating the liquid portion until the concentration of acetone in water is about 70% and crystallizing the lactoflavin from this mixture.

8. In the preparation of crystalline lactoflavin the steps of eluting an adsorbate containing lactoflavin with a mixture of acetone and water containing about 80% acetone, concentrating the eluate, adding ethyl alcohol to give a concentration of about 50% alcohol, separating solids resulting therefrom, heating the liquid fraction to remove alcohol, adding acetone to the resulting solution to give a concentration of about 10 parts by volume of acetone and 1 part of water, separating the extraneous matter precipitated thereby, heating to remove the acetone, extracting the liquid with ethyl ether, removing the ether and adding acetone to give a concentration of 10 parts of acetone and 1 of water, separating any residue, concentrating the liquid portion until the concentration of acetone in water is about 70% and crystallizing the lactoflavin from this mixture.

9. A method for separating lactoflavin comprising adsorbing the lactoflavin, eluting the adsorbate with a relatively large quantity of an acetone-water mixture at slightly elevated temperature, removing acetone and concentrating, treating the concentrate with alcohol, removing the precipitate, adding acetone to the liquid portion to give a concentrated acetone-water mixture, separating the precipitate, extracting the liquid with ethyl ether, removing the ether from the aqueous portion, subjecting this fraction to a concentrated acetone-water mixture, removing the precipitate, concentrating to remove a portion of the acetone and cooling the concentrated solution to crystallize lactoflavin, washing the crystals with acetone, alcohol and ether and drying them.

50 10. A method for separating lactoflavin comprising adsorbing the lactoflavin, eluting the adsorbate with a relatively large quantity of an acetone-water mixture at slightly elevated temperature, removing acetone and concentrating, treating the concentrate with alcohol, removing the precipitate, adding acetone to the liquid fraction to give a concentrated acetone-water mixture, separating the precipitate, extracting the liquid fraction with ethyl ether, removing ether from the aqueous fraction, subjecting this fraction to a concentrated acetone-water mixture, removing the precipitate, concentrating to remove a portion of the acetone and cooling the concentrated solution to crystallize lactoflavin, washing the crystals with acetone, alcohol and ether and drying them and returning the precipitate from the alcohol treatment to the elution step.

70 11. A method for separating lactoflavin comprising adsorbing the lactoflavin, eluting the adsorbate with a relatively large quantity of an acetone-water mixture at slightly elevated temperature, concentrating to remove acetone and evaporating to dryness in the presence of air, leaching the dried concentrate with water, sepa-

rating the liquid fraction, concentrating it and adding acetone to produce a concentrated acetone-water mixture, separating the precipitate, treating the liquid portion with ethyl ether, removing ether from the aqueous portion, adding 5 acetone to produce a concentrated acetone-water

mixture, removing the precipitate, concentrating to remove a portion of the acetone and cooling to crystallize lactoflavin, washing the crystals with acetone, alcohol and ether and drying them.
